UNITED STATES PATENT OFFICE.

JONATHAN E. WOODBRIDGE, OF DULUTH, MINNESOTA, ASSIGNOR TO THE ELECTRICAL ADVERTISING AND SIGN COMPANY, OF MAINE.

ELECTRIC-LIGHT DISPLAY SYSTEM.

SPECIFICATION forming part of Letters Patent No. 546,799, dated September 24, 1895.

Application filed July 8, 1895. Serial No. 555,212. (No model.)

To all whom it may concern:

Be it known that I, JONATHAN E. WOODBRIDGE, a citizen of the United States, residing at Duluth, in the county of St. Louis and 5 State of Minnesota, have invented a new and useful Improvement in Electric-Light Display Systems, of which the following is a specification.

My invention relates to a device for producing letters, words, characters, and designs of light, and for changing the delineations at pleasure, the same to be employed for purposes of signs, advertising, and public notices and similar uses in conspicuous places.

15 In carrying out my invention I employ a display-board studded with a large number of electric lamps that are to be lighted in groups, each group representing a letter of a word or name, a character, or a design.

20 Each lamp is connected to one main-line wire and to an electromagnetic switch, and each magnetic switch is in turn connected to the other main-line wire, and a hand-switch is employed in one main-line wire. As each

25 magnetic switch is operated by the depression of its armature, a circuit including one lamp is established which lights said lamp, the armature being held by the magnet and the lamp remaining lighted until the circuit is broken

30 by opening the hand-switch. This operation can be performed with every lamp on the display-board, the lamps being lighted at pleasure in groups representing the letters of a word or words or characters or ornamental designs.

35 Any desired means may be employed for bringing the electromagnetic switches into action, but I prefer and usually employ a writing-board consisting of a backing of insulating material upon which are a multiplicity

40 of metal disks or contacts, agreeing in number with the magnetic switches and lamps and in arrangement corresponding with the lamps. A wire extends from each metal disk or contact to the magnetic switch connected to

45 the lamp of corresponding position, and a line extends from one of the main lines to a hand-operated metal pencil or stylus. The metal pencil or stylus is drawn across the faces of the metal disks or contacts in outlining letters, designs, or characters, and the disks touched determine the lamps in the lighted

groups. The pencil or stylus as it touches each successive disk establishes a circuit that draws down the armature of the magnetic switches successively and closes the circuits 55 through the corresponding lamps.

In the drawings, Figure 1 is a diagrammatic view illustrating my invention. Fig. 2 is a diagrammatic view illustrating the devices in one complete circuit. Fig. 3 is a 60 diagrammatic view illustrating my invention applied to the three-wire system. Fig. 4 is a diagrammatic view illustrating a modification in the arrangement of the parts, and Fig. 5 is a side elevation of a way of mechanically operating the magnetic switch.

A represents a portion of a display-board studded with a large number or multiplicity of incandescent electric lamps a. The board may be of any size and contain any desired 70 number of lamps, according to the requirements to be fulfilled, and they are preferably arranged in rows.

B represents a number of electromagnetic switches, which are preferably secured to a 75 board or frame and agreeing in number and position with the electric lamps.

Any kind of electromagnetic switch may be employed, but I prefer and have shown the same as constructed with a helix c, an 80 iron core d, an insulated screw d', an iron frame e, and a screw e', passing through and attaching the magnet to the supporting board, a pivoted iron armature f on the frame e, and a back stop-screw f', a contractile 85 spring 2, and a wire 4 from the frame e to the wire helix c.

Wires 5 connect each magnetic switch B with a lamp a of corresponding position and wires 9 connect the lamps with a main line 10. 90 A main line 20, in which is a switch 3, is connected to each magnet at its insulated screw d' by wires 7.

The armatures f may each be mechanically depressed to contact with the cores d to complete circuits between the main lines 10 and 20, through the wires 9, lamps a, wires 5, helices c, wires 4, frames e, armatures f, cores d, screws d', and wires 7 to light the lamps. The magnetic switches are to be operated in 95 groups as desired to produce letters, words, names, characters, or designs in light upon the

display-board of lamps, and the lights will remain lighted until by the opening and successive closing of the hand-switch 3 or equivalent means all are turned off simultaneously, 5 preparatory to making other letters, words, characters, or designs of light.

I prefer to operate the magnetic switches B in a more convenient and expeditious manner than by a mechanical depression of the 10 armatures f, as shown in Fig. 5. This I accomplish by means of a writing-board C, Figs. 1 and 4, consisting of a backing of insulating material, on which are a multiplicity of metal disks or contacts b, agreeing in number and 15 arrangement with the incandescent electric lamps a. From each metal disk or contact b extends a wire 12 to the screw e' of the magnetic switch of the corresponding lamp. A wire 15 extends from the main line 20 to a 20 metal pencil or stylus 14, having an insulated handle, so as to be moved by hand. This metal pencil or stylus 14 is drawn over the faces of the metal disks or contacts to outline and produce in light letters in spelling words 25 or names or designs or characters, and the respective disks or contacts touched thereby determine which lamps are to be lighted. As the pencil touches each disk b, a local circuit is established from the line wire 20, through the 30 wire 15, pencil 14, disk b, wire 12, screw e', frame e, wire 4, helix c, wire 5, lamp a, wire 9, to line-wire 20, which lights the lamp, and the helix draws down the armature f of the magnetic switch, and in so doing the circuit 35 is established from the wire 5 of the lamp, through the helix c, wire 4, frame e, armature f, core d, screw d', wire 7 to the line 20, and the lamp is kept burning until the switch 3 is opened and the circuit broken, which puts 40 out all the lamps at once and breaks each individual lamp-circuit at the armatures f, so that any new word design, &c., may be afterward made in light.

It is obvious that with large boards the 45 lamps may be divided into sections, each operated by a separate throwing-out switch, so as to obviate the necessity of putting out all the lights at once.

In the drawings, Fig. 3, I have shown the 50 application of my invention to the three-wire system, such as is so generally employed in large cities. In this system there is a positive main wire 25, a negative main wire 30, and a neutral main wire 35, coupled to two dynamos 55 D D' in the usual manner. The electric lamps a of the display-board are connected by wires 9, in groups, alternately to the main + and - wires 25 30, and the electro-magnetic switches B' are all connected by wires 7 to the neutral 60 wire 35 and by wires 5 to the lamps. They may be operated mechanically or, as hereinbefore described, by a writing-board C' and stylus or pencil.

In Fig. 4 I have shown a modification of my 65 invention, the object of which is to light the electric lamps in the manner hereinbefore described, but only dimly, or with a small

amount of light, which, with a ground or colored globe, is practically invisible, and afterward, by means of a switch, to flash the entire 70 word, name, design, or character brightly into vision all at once. This is accomplished by employing a main wire 22 and an auxiliary wire 27, with the display-board A of lamps a connected to the wire 27. The wires 22 and 27 75 are connected by a hand-adjustable resistance 23, through which and the wire 27 the current passes to the lamps during the period of tracing or writing out the letters, characters, or designs, the hand-switch 24 being open. 80 After the letters, &c., are dimly written out the hand-switch 24 is closed to flash all the lamps at once to view and show the entire word, character, or design. The hand-switch 28 is to be opened to put the lights all out. 85 The writing-board is to be employed when desired in this as in the other arrangements shown, and I prefer to employ a lamp in the wire from the main wire 22 to the pencil or stylus. 90

In Fig. 4 wires 15 connect the lamps a to the frames of the electro-magnetic switches B, and the main wire 20 is connected by wires 17 to the helices, and the helices in turn to the insulated screws of the cores, the wires 42 from 95 the disks of the writing-board going to the insulated screws of the core, so that the currents through the helices from the writing-board will draw down the armatures and establish the permanent circuits to the lamps 100 through said armatures.

I have shown in Fig. 5 a means for operating the electro-magnetic switches by hand, in which a stem 47 is connected to the armature f², and a button 18 upon the stem is in an 105 opening in a surface-board 19, the surface of the button projecting slightly, so that when the finger is passed over the surface of the board the buttons will be depressed and the circuits through the armatures closed. If the 110 buttons 18 and stems 47 are of metal, the armatures can be depressed by the electrical action produced by a wire brush connected in the circuit and drawn over the buttons by hand in a manner similar to the operation of 115 the stylus or pencil 14 and similarly connected to a main-line wire.

I claim as my invention—

1. The combination with a display board having a multiplicity of electric lamps, of 120 electro-magnetic switches one for each lamp and circuit connections through each lamp and its electro-magnetic switch and means for closing each of the circuits whereby the circuit that is closed through any lamp is 125 maintained by the magnet holding switch, and a hand switch in the main circuit to turn off the current and extinguish the lamps and break the circuits at the switches, substantially as specified.

2. The combination with a display board having a multiplicity of electric lamps, of 130 electro-magnetic switches and circuit connections through each lamp and its electro-

magnetic switch whereby the circuit that is closed through any lamp is maintained by the magnet holding switch, and a hand switch in the main circuit to turn off the current and extinguish the lamps and break the circuits at the switches, a writing board with contacts corresponding in number and position to the lamps, branch circuit connections to the contacts and a stylus circuit-closer and flexible connections thereto for actuating the switches electrically, substantially as specified.

3. The combination with a display board having a multiplicity of electric lamps, of electro-magnetic switches and circuit connections through each lamp and its electro-magnetic switch whereby the current that is closed through any lamp is maintained by the magnet holding switch, and a hand switch in the main circuit to turn off the current and extinguish the lamps and break the circuits at the switches, a resistance in the main circuit for lessening the current to the lamps and a switch for short circuiting such resistance substantially as specified.

25 4. The combination with a display board having a multiplicity of electric lamps, of electro-magnets one for each lamp, circuit connections passing through the armatures

and cores for causing the armatures to act as switches, branch circuits from the magnets 30 and a circuit closing stylus for energizing the electro-magnets and closing their switches, substantially as specified.

5. The combination with a display board having a multiplicity of electric lamps, of 35 electro-magnetic switches corresponding in number and position to the lamps, circuit connections through each lamp and its corresponding electro-magnetic switch, means for depressing the armatures of any desired 40 number of said electro-magnetic switches to complete a permanent electric circuit through said electro-magnetic switches and lamps to light the lamps, which circuits are maintained by the magnets holding the switch armature, 45 and a hand switch in the main circuit to turn off the current and extinguish all the lamps at once and break the currents at the respective switches, substantially as specified.

Signed by me this 21st day of June, A. D. 50
1895.

JONATHAN E. WOODBRIDGE.
